(57) **CLAIM**

The ornamental design for a folding wagon, as shown and described.

DESCRIPTION

FIG. 1 is a top, front and right side perspective view of a folding wagon showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front and right side perspective view showing the folding wagon in folded state;

FIG. 10 is an enlarged view of the portion 10 in FIG. 1; and, FIG. 11 is an enlarged view of the portion 11 in FIG. 1.

The evenly dashed broken lines illustrate portions of the folding wagon. The unevenly dashed broken lines define the boundaries of the enlarged view. None of broken lines form part of the claimed design.

1 Claim, 11 Drawing Sheets
